UNITED STATES PATENT OFFICE.

FLOYD D. STOWE, OF WILMINGTON, DELAWARE, ASSIGNOR, BY MESNE ASSIGNMENTS,
TO E. I. DU PONT DE NEMOURS AND COMPANY, A CORPORATION OF DELAWARE.

DISK-FEEDER.

1,342,189.

Specification of Letters Patent.

Patented June 1, 1920.

Application filed February 26, 1914. Serial No. 821,231.

To all whom it may concern:

Be it known that I, FLOYD D. STOWE, of Wilmington, in the county of New Castle, and in the State of Delaware, have invented 5
a certain new and useful Improvement in Disk-Feeders, and do hereby declare that the following is a full, clear, and exact description thereof.

My invention relates especially to conveyers adapted for feeding blanks, and it relates more particularly to an apparatus designed for feeding blanks in the form of disks, such as those used for providing the ends of cylindrical sheet metal kegs, although it is applicable to many other uses.

The object of my invention is to provide a conveyer which will effectively and uniformly feed blanks, as for example, blanks received from a blanking press and convey 10 these blanks to an elevated position where they may be fed into the forming press or other apparatus in which the blanks are to be utilized. A further object of my invention is to provide an apparatus of this kind 15 in which the blanks are discharged from the conveyer into the forming press or other apparatus in which the blanks are to be used one at a time and at given intervals of time, and in which, furthermore, any blanks 20

in addition to those needed for the forming press or other apparatus are discharged separately by the conveyer without being fed to the forming press or other apparatus referred to.

While my invention is capable of being carried out in many different ways, for the purpose of illustration, I have shown only one form of my invention in the accompanying drawings, in which,

Figure 1 is a vertical elevation partly in section of a conveyer made in accordance with my invention.

Fig. 2 is a front view of the same.

Fig. 3 is a top view of the same, and

Fig. 4 is a transverse section taken on line 4—4 of Fig. 1.

In the drawings I have shown an inclined conveyer which is supported upon a base 1, having ears 2, with holes to secure the apparatus to the floor or other support. This base 1 is provided with three bushings

3 to receive ends of three conveyer screws 4, 5 and 6 to the ends of which are secured gears 7, 8 and 9. The shafts are driven in the same direction and at the same speed 55 through the intervention of an idler gear 10 carried on a stud shaft 11 which extends up through the base 1 and is secured thereto by means of a nut 12. The base 1 has a gear box 13 attached to the under surface 60 thereof by means of bolts 14 and nuts 15 for the purpose of inclosing the gears 7, 8, 9 and 10. Upon the upper face of the base 1 there are a pair of arms 16 to support a platform 17 which receives the blanks, such 65 for example, as disk blanks, the platform 17 being attached to the arms 16 by screws 18. At its side the platform has a pair of lateral guides 19 so as to guide the blanks to the screws 4, 5 and 6. The platform 16 70 also has a pair of tracks 20 to allow the blanks to slide more readily thereon. The base 1 also receives four rods 21, which are secured to the base 1 by means of nuts 22 and which support on their upper ends an 75 end frame 23, which end frame is maintained in place by nuts 24 on the ends of the rods 21. The two screws 4 and 6 have their upper ends journaled in the end frame 23. The screw 4, however, passes through the 80 end frame 23 and is provided above the end frame with a beveled gear 25 which meshes with a beveled gear 25^a on a shaft 26 supported by bushings 27 in bearings 28 on the end frame 23. The shaft 26 has a pulley 85 29 on its end to receive power from any suitable source. The beveled gears 25 and 25^a are carried in a gear box 30 which is formed on the end plate 23, and which has a removable cover 31 for inclosing said 90 gears. The screw 5 is shorter than the screws 4 and 6 and terminates below the end plate 23. This screw 5 has its upper end supported by a sleeve 32 which extends part way around the same and which is supported upon a bracket 33 attached to a cross arm 34 extending between the rods 21 which are located at the rear of the conveyer. A discharge plate 35, having tracks 35^a and side guides 35^b, projects into the conveyer 95 beneath the end plate 23 and over the end of the screw 5 to receive the blanks as they 100

fall by gravity from the conveyer and over the end of the screw 5. This discharge plate is supported upon the two rear rods 21 by clamping brackets 36. Near its end the discharge plate 35 is provided with a pair of stop pins 37 and 38 operating through openings in the discharge plate, which are screwed into the ends of a rocking lever 39, pivoted to the under side of the discharge plate 35 in a bracket 40 on a shaft 41. The end of the shaft 41 has an upwardly directed arm 42 to which is attached a connecting rod 43 which connects the arm 42 with an eccentric 44 which may be attached to a shaft 45 carried by a forming press or any other apparatus, to which the blanks are to be fed from the conveyer. Immediately above the discharge plate 35 there is secured to the same a side chute 46 which is secured 20 to the discharge plate 35 by means of adjusting screws 47 and nuts 48 passing through ears 49 and 50 upon the discharge plate 35 and the side chute 46 respectively. The side chute 46 has a plurality of tracks 25 46^a and side guides 46^b. A pivoted guide 51 is supported in journal brackets 52 at the front of the side chute 46 and has three forwardly directed guiding arms 53 and a rearwardly directed arm 54 which operates 30 in a slot 55 in the side chute 46 and a slot 56 in the discharge plate 35.

In the operation of the conveyer, blanks are fed at intervals to the platform 17 from a blanking press or in any other suitable 35 manner. The screws 4, 5 and 6, being rotated from the pulley 29 by means of the beveled gears 25 and 25^a and the gears 7, 8, 9 and 10, convey the blanks one after another upwardly in the space between the several screws in an effective and uniform manner until the blanks have been conveyed 40 above the end of the screw 5. The inclination of screws 4, 5 and 6 is advantageous in that the blanks, while being fed, rest on screw 5 and are guided upwardly by the combined action of the three screws which still permit removal of a defective blank at any point in its travel along the screws, since with the inclined arrangement the 45 screws need not inclose the blanks so as to prevent removal of the latter. The pivoted guide 51 is arranged so that its guiding arms 53 are normally raised up above the level of the discharge platform 35. In this 50 position of the guide, when a blank reaches the discharge platform 35 it passes downwardly upon the discharge platform beneath the arms 53, thereby elevating the arm 54 and depressing the guiding arms 53. This 55 blank will then be stopped by the stop pin 38 where it will be held until the rocking arm 39 is rocked by the eccentric 44 so as to withdraw the pin 38 and elevate the pin 37. The pin 37 in its elevated position then stops

the blank which falls by gravity in front 65 of the pin 38 to a position in front of the pin 37. When the eccentric 44 moves in such a manner as to withdraw the pin 37 from above the discharge plate 35, the blank which has been retained by the same 70 falls by gravity from the end of the discharge plate 35 into a forming press or any other apparatus designed for receiving the blanks. In this movement the pin 38 will be again elevated so as to prevent the next 75 succeeding blank from being fed into the forming press or other apparatus designed for receiving the blanks. The blank which is retained in this manner by the pin 38 cannot be fed into the forming press or other 80 apparatus referred to until the eccentric has made another complete revolution, so as to first withdraw the pin 38, elevating the pin 37 and then subsequently withdraw the pin 37, elevating the pin 38. After the conveyer 85 has begun to operate, in the normal operation thereof, there will be a blank fed into the discharge plate at about the time that the pin 37 has been withdrawn to release this blank to be fed into the forming press 90 or other apparatus. When the pin 38 is elevated there will thus normally be a blank held in place above the pin 38 beneath the arm 54. Should another blank be fed to the discharge platform while the parts are 95 in this position the guiding arm 53 will lift said blank into the side chute 46, where it will be discharged from the conveying apparatus to a receptacle of any desired character. With devices of this character only 100 a single blank may be fed into the forming press or other similar apparatus for one revolution of the eccentric 44. Any blanks in excess of this which are fed upwardly by the screws 4, 5 and 6 are discharged at the 105 side chute 46.

While I have described my invention above in detail, I wish it to be understood that many changes may be made therein without departing from the spirit of my invention.

I claim:

1. In a feeder, means for feeding blanks, means for discharging the blanks one at a time, comprising a chute and a rocking detent therein adapted to form a stop for each blank as it is fed, and a deflecting means for excess blanks comprising a chute adjacent said first mentioned chute, and a rocking deflector adapted to be engaged by a blank 115 when against said detent for deflecting blanks to said last mentioned chute.

2. In a feeder, means for feeding blanks, means for discharging the blanks one at a time, comprising an inclined delivery chute 125 and a second chute for excess blanks located adjacent the same, a stop in said delivery chute adapted to be actuated periodically to

permit blanks to pass along said delivery chute, and a deflector engaged by a blank when against said stop for deflecting blanks to said chute for excess blanks.

5 3. In a feeder, a plurality of inclined screws adapted to engage the members fed, the lower of said screws being shorter than the others whereby the members fed may

fall away from the remaining screws, and a delivery chute adjacent said short screw. 10

In testimony that I claim the foregoing I have hereunto set my hand.

FLOYD D. STOWE.
